Primary Examiner — Ruth McInroy(74) *Attorney, Agent, or Firm* — Thorpe, North & Western LLP(57) **CLAIM**

I claim the ornamental design for a portable cordless microwave food warmer, as shown and described.

DESCRIPTION

FIG. 1 is a front perspective view of the portable cordless microwave food warmer in accordance with my invention; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a front perspective view thereof in an open configuration.

The broken lines shown in FIGS. 1-8 are for illustrative purposes only and form no part of the claimed design.
